UNITED STATES PATENT OFFICE.

JOHN F. KREYČIK, OF LYNCH, NEBRASKA.

CLOTHES-WASHING DEVICE.

1,182,093.

Specification of Letters Patent.

Patented May 9, 1916.

Application filed August 6, 1915. Serial No. 43,983.

To all whom it may concern:

Be it known that I, JOHN F. KREYČIK, a citizen of the United States, residing at Lynch, in the county of Boyd and State of Nebraska, have invented certain new and useful Improvements in Clothes-Washing Devices, of which the following is a specification.

This invention relates to improvements in clothes washing devices and has for its object to provide means whereby a continuous stream of water is forced through the clothes being washed.

Another object of the invention is to provide automatic means for forcing water through the clothes being washed.

Still another object of the invention is to provide a combined clothes pounder and suction device for drawing water through clothes being washed.

With the above and other objects in view which will hereinafter be more fully explained, I have invented the device illustrated in the accompanying drawings in which:

Figure 1, is an elevational view of my invention, and Fig. 2, is a vertical sectional view of the device and a tub of washing in which it is operatively located.

Like reference characters indicate like parts throughout the specification and in the several views in the drawings in which—

1 indicates my invention which consists of an outer inverted funnel shaped member 2, the spout 3 of which is divided at its upper end 4 into two arcuate overhanging spout portions 5 and 6. Located within the member 2 and having its edge 7 projecting slightly therebelow is another mounted funnel shaped member 8 which is of same size or

smaller than the member 2 and is held spaced apart therefrom by means of the connecting members 9 whereby a space 10 is provided entirely around the member 8 with an inlet 11 extending all around the device. 45

When the device is placed in a boiler 12 with the portion 7 seated upon the bottom 13 of the boiler, steam will be generated in the chamber 14, which will pass out through the tube 3 and in so doing will suck water up 50 through space 10 and through the tube 3 and cause it to be ejected through the outlets 15 and 16 of the members 5 and 6, from which it will pass back into the boiler 12. Thus a continuous circulation of water will pass 55 through the clothes 17 in the boiler when the latter is being heated. When the device is used as a clothes pounder the parts 5 and 6 are grasped by the hands of the operator and the pounder operated up and down upon 60 the clothes forcing water through the clothes with each successive up and down movement.

Having now described my invention that which I claim to be new and desire to procure by Letters Patent is:— 65

A clothes pounder consisting of a conically shaped inner member a similar outer member terminating in a tube, said members being spaced apart, said tube terminating in 70 a pair of arcuate handle forming tubes, said inner member projecting below said outer member, said inner member having an opening into said outer member.

In testimony whereof I affix my signature 75 in the presence of two witnesses.

JOHN F. KREYČIK.
